OIL SEALING DEVICE FOR
JOURNAL BOXES

Ernest Armstrong, West Collingswood, N. J., and
John Edward Thebaud, Philadelphia, Pa.; said
Thebaud assignor to said Armstrong

Application October 12, 1934, Serial No. 748,090

8 Claims. (Cl. 286—6)

This invention relates to oil sealing devices for journal boxes.

There is provided at the wheel end of a railway journal box, a narrow dust guard pocket 5 for holding a flat dust guard surrounding the car wheel axle. It is one of the objects of this invention to provide an oil sealing device to replace the dust guard, which will not only exclude the dust, but will at the same time retain the 10 lubricating oil within the journal box, to conserve the oil and maintain ample lubrication, reducing friction and consequently lowering the fuel consumption in the running of trains, besides making it possible, by means of the maintenance of ample lubrication, to run trains much 15 faster.

A further object of this invention is to provide an oil sealing device for journal boxes which, while fitting within the narrow pocket of the 20 journal box will, with the use of a special formation of gasket of leather or the like, seal against the inner wall of said pocket and around the circular opening therein, through which the axle passes, and at the same time will seal against 25 the running surface of the axle in a zone in the plane of the dust guard pocket, by means of an inturned circumferential lip or neck portion to the gasket, having within this neck portion and fixed thereto, a ring of felt or the like, in contact with the running surface of the axle, to 30 assist in holding back the oil.

A further object in connection with that of providing a gasket, is to provide wedging means 35 for holding the body of the device forcibly up against the flat portion of the gasket, where it contacts the inner wall of said guard pocket.

Another object of this invention is to provide 40 an adjustable, flat sectioned, metal ring around said neck, for holding said felt ring and said lip in close circumferential contact with said axle.

A further object is to provide with said metal ring, an adjustable and locking clamp, affording means for adjusting the pressure of said metal ring against said neck, and in turn, exerting a 45 pressure contact of said felt ring and said lip, against the running surface of the axle.

Another object of this invention is to provide 50 an elastic means for practically maintaining an adjusted pressure of said ring, on said neck, while taking up slack due to wear of said lip and said felt ring.

And a further object of this invention is to provide 55 a check to the adjustment of said metal ring, to limit the tightening thereof, and thus prevent the one who makes the adjustment, from

clamping the felt neck portion of the gasket too tight, which would force a strong frictional engagement of said felt ring upon said axle, tending to destroy the seal, or burn it out.

With these and other objects, which will hereinafter appear, our invention is illustrated in the accompanying drawings, is hereinafter described, its functions are explained and what we claim is set forth.

In the drawings,

Figure 1 is an elevation of our oil sealing device, with adjustable holding means.

Figure 2 shows in section the same device housed in part of a journal box, including the dust guard pocket and axle.

Figure 3 is a sectional elevation of our device similar to part of that shown in Figure 2, but here enlarged.

Figure 4 is an enlarged elevation of the adjustable clamping parts of the device.

Figure 5 is a perspective view of that end of the metal holding ring which has a toothed sleeve fixed thereto.

Figure 6 is an elevation of the swivelled bolt with its locking pin.

Figure 7 is a perspective view of the double wedging member.

Figure 8 is an end elevation of the plate body of our device, including the tapered, channeled wedge seat.

In the figures, the dust guard pocket 10, of Figures 2 and 3, is shown in the journal box fragment 11, to have an inner wall 12 and an outer wall 13. Within the pocket 10, is positioned the oil seal device 14, having a plate body 15, in which is the large hole 16. Passing through the hole 16 and the holes 17 and 18, of the respective inner and outer walls 12 and 13, of the pocket 10, is the car wheel axle 19. Held tightly between the plate body 15, and the inner wall 12, is the flat portion 20, of the gasket 21, which is held in oil sealing contact with the wall 12, by the forced engagement of the double wedge member 22, with the outer wall 13, and with the two tapered wedge seats 23, which are fixed upon one face of the plate body 15, between which seats 23 is the hole 16. Each wedge seat 23 has a longitudinal groove 24, in which slidably fits a tapered blade 25, of the double wedge member 22.

The wedge member 22 (see Figure 7) has a horizontal bar portion 26, integral with the tapered blades 25, and is provided with two projecting screws 27, as means forming an anchorage to which a tool can be attached for withdrawing the wedge member 22, whenever desired, particularly

when making an adjustment to the seal. Integral with the flat portion 20, of the gasket 21, is the neck flange 28, having an inturned lip 29, beveled at 30. Within the neck flange 28 is a 5 felt ring 31, in contact with the running surface of the axle 19. The felt ring 31 is attached to the neck flange 28, and may be fixed thereto by cement or rivets, or both. Surrounding the neck flange 28, is the split metal ring 32, having out- 10 turned ends 33 and 34. Fixed upon the plate body 15, is the nut piece 35, which is next to the ring end 33. Fixed upon the ring end 34, is the bolt sleeve 36, (see also Figures 4 and 5), having a tooth 37, projecting from its outer end. The bolt 15 passes through the sleeve 36, and the ring end 33, and engages the nut piece 35. The bolt 38 has an enlarged shank portion 39, with a shoulder 40. Projecting from the shoulder 40, next to the threaded portion of the bolt 38, is a short pin 41, 15 positioned to engage the tooth 37 on the sleeve 36. Surrounding the sleeve 36, and in bearing contact with the ring end 34, and the shoulder 40, of the bolt 38, is a coiled compression spring 42. There is hinged to the bolt shank 39, at the hinge 43, 20 an extension 44, having a cross slot 45 in its end. This extension 44 is made long enough to reach outside the narrow pocket 10, when lifted up to be in line with the bolt shank 39, as is shown at 44^a of Figure 1, so as to be easily engaged by a screw 25 driver, for turning the bolt 38.

Having described one embodiment of our invention herein illustrated, we will now refer to its installation and its functions. The oil sealing device is installed as follows: Prior to entering the axle 35 19, into the journal box 11, the bolt 38 is turned to loosely engage the ring ends 33 and 34, as shown in Figure 4. The split-ring 32 will then loosely engage the neck flange 28. In this condition, the device is dropped into the pocket 10, with the 40 bolt extension 44, positioned near the top of the pocket 10. Next the axle 19 is entered through the device hole 16, passing within the beveled edge 30, of the inturned lip 29, and the felt ring 31, into its proper position, engaged by the usual bearing brass, not shown. The wedge member 22 45 is driven down engaging the seat grooves 24, to force the flat portion 20, of the gasket 21, into oil sealing engagement with the wall 12, but prior to positioning the wedge member 22, the bolt extension 44 is lifted up to be in line with the bolt shank 39, (lifted as at 44^a of Figure 1) having the 50 free end outside the pocket 10, where a screw driver is engaged with the slot 45, to turn the bolt 39, into the nut piece 35, to bring the shoulder 55 40, of the bolt 38, into contact with the spring 42. (See Figure 4.) A further turning of the bolt 38, compresses the spring 42, forming a tightening action to draw the out-turned ring ends 33 and 34, closer together. Upon a continued turning of the 60 bolt 38, to tighten the ring 32, the spring 42 is further compressed, until the bolt pin 41 engages the tooth 37, (as in Figure 1), on the fixed sleeve 36, arresting any further turning of the bolt 38 and stopping any further tightening of the ring 65 32, at a point of desired compressive adjustment of the felt ring 31, in contact against the car wheel axle 19, to produce a pressure just sufficient to cause a proper oil seal during the running of the axle 14, without undue friction.

70 The spring 42 should be of such a strength, for its length, that when it is compressed to a point where the pin 41 stops against the tooth 37, the spring pressure exerted to draw up the ring ends 33 and 34, will cause the desired adjusted pressure contact between the felt ring 31, and the axle 75

19. Then, as wear takes place, the spring 38 will cause a take-up by the ring 32, to preserve the proper oil sealing contact of the felt ring 31, and the lip 29, with the axle 19.

If, due to further wear, of the felt ring 31, the tooth 37 works away from the pin 41, (as relatively positioned in Figure 4), another turn or more of the bolt 38 can be made in further adjustment, to take up this wear, until the pin 41 again locks against the tooth 37. After any turning of the bolt 38, as above described, the bolt extension 44 is dropped back into the pocket 10, to be at an angle to the bolt shank portion 39, to practically lock the bolt 38 against accidental turning. This locking feature together with the take-up, afforded by the spring 42, and the stop, to limit the turning of the bolt 38, to prevent undue tightening of the ring 32, provides an adjustment of the felt ring 31, and the lip 29, in contact with the running surface of the axle 19, that insures a 20 practical and durable oil seal. After setting and adjusting the ring 32, in tightness and turning the bolt extension 44 down into the pocket 10, the double wedge member 22 is put in place and forced down to seal the gasket portion 20 against 25 the wall 12.

With the oil thus sealed in and conserved, and the axle lubrication maintained, friction, under running conditions, will be greatly reduced, leaving more engine power for faster travel, as well 30 as effecting such an economy in the use of fuel, that the cost of installing this oil seal will soon be offset by the economy effected.

While we have shown and described one embodiment of our invention, changes can be made 35 therein without departing from the spirit and scope thereof. We therefore wish to include all forms and changes which come within the purview of the following claims.

We claim:

1. An oil sealing device adapted for use, below the open end and between the walls of a narrow pocket around an axle in a journal box, comprising a body plate have a hole therethrough, through which passes said axle, a gasket, a flat portion to 45 said gasket between one of said walls and said body plate and surrounding said axle, wedging means between said body plate and the other of said walls to force said body plate to compress said flat portion of said gasket against the wall 50 it adjoins, said wedging means including two parallel sets of long tapered, complemental members, positioned normal to said open end, of said pocket, and spaced to have one of said sets on one side of said axle, and the other set on the opposite side of said axle, one member in each set being fixed or integral with said body plate, and the other member, complemental to the fixed member, being movable, a grooved face on one member of each set, positioned next to its complemental 60 member, and a blade portion slidingly fitting said grooved face on each of said last mentioned complemental members, the taper between the members in each set being such, that as the movable members are forced in, said wedging means will 65 exert a side pressure between said body plate and said flat portion of said gasket, and a neck portion to said gasket integral with said flat portion, surrounding said axle.

2. An oil sealing device adapted for use, below 70 the open end and between the walls of a narrow pocket around an axle in a journal box, comprising a body plate having a hole therethrough, through which passes said axle, a gasket, a flat portion to said gasket between one of said walls 75

and said body plate and surrounding said axle, wedging means between said body plate and the other of said walls to force said body plate to compress said flat portion of said gasket against

- 5 the wall it adjoins, said wedging means, including two parallel sets of long tapered, complementary members, positioned normal to said open end, of said pocket, and spaced to have one of said sets on one side of said axle, and the other 10 set on the opposite side of said axle, one member in each set being fixed or integral with said body plate, and the other member, complementary to the fixed member, being movable, a grooved face on one member of each set, positioned next 15 to its complementary member, and a blade portion slidingly fitting said grooved face on each of said last mentioned complementary members, the taper between the members in each set being such, that as the movable members are forced in, 20 said wedging means will exert a side pressure between said body plate and said flat portion of said gasket, a neck portion to said gasket integral with said flat portion, surrounding said axle, and a felt ring between said neck portion and said 25 axle.

3. An oil sealing device adapted for use, below the open end and between the walls of a narrow pocket around an axle in a journal box, comprising a body plate having a hole therethrough, through which passes said axle, a gasket, a flat portion to said gasket between one of said walls and said body plate and surrounding said axle, wedging means between said body plate and the other of said walls to force said body plate to compress said flat portion of said gasket against the wall it adjoins, said wedging means including two parallel sets of long tapered, complementary members, positioned normal to said open end, of said pocket, and spaced to have one of said sets 40 on one side of said axle, and the other set on the opposite side of said axle, one member in each set being fixed or integral with said body plate, and the other member, complementary to the fixed member, being movable, a grooved face on one member 45 of each set, positioned next to its complementary member, and a blade portion slidingly fitting said grooved face on each of said last mentioned complementary members, the taper between the members in each set being such, that as the movable members are forced in, 50 said wedging means will exert a side pressure between said body plate and said flat portion of said gasket, a neck portion to said gasket integral with said flat portion, surrounding said axle, an inturned circumferential lip to said neck, and a felt ring between said neck and said axle.

4. An oil sealing device adapted for use, below the open end and between the walls of a narrow pocket around an axle in a journal box, comprising a body plate having a hole therethrough, through which passes said axle, a gasket, a flat portion to said gasket between one of said walls and said body plate and surrounding said axle, wedging means between said body plate and the other of said walls to force said body plate to compress said flat portion of said gasket against the wall it adjoins, said wedging means including two parallel sets of long tapered, complementary members, positioned normal to said open end, of 60 said pocket, and spaced to have one of said sets on one side of said axle, and the other set on the opposite side of said axle, one member in each set being fixed or integral with said body plate, and the other member, complementary to the fixed 65 member, being movable, a grooved face on one

member of each set, positioned next to its complementary member, and a blade portion slidingly fitting said grooved face on each of said last mentioned complementary members, the taper between the members in each set being such, that as the 5 movable members are forced in, said wedging means will exert a side pressure between said body plate and said flat portion of said gasket, a neck portion to said gasket integral with said flat portion, surrounding said axle, and a holding ring member surrounding said neck portion to force the same toward said axle.

5. An oil sealing device adapted for use, below the open end and between the walls of a narrow pocket around an axle in a journal box, comprising a body plate having a hole therethrough, through which passes said axle, a gasket, a flat portion to said gasket between one of said walls and said body plate and surrounding said axle, wedging means between said body plate and the other of said walls to force said body plate to compress said flat portion of said gasket, a neck portion to said gasket integral with said flat portion, surrounding said axle, and a holding ring member surrounding said neck portion to force the same toward said axle, said holding ring member comprising a split ring, adjacent ends to said split ring, and a clamping bolt with a nut 20 for drawing said ends together. 25

6. An oil sealing device adapted for use between the walls of a narrow pocket around an axle in a journal box, comprising a body plate having a hole therethrough, through which 30 passes said axle, a gasket, a flat portion to said gasket between one of said walls and said body plate and surrounding said axle, wedging means between said body plate and the other of said walls to force said body plate to compress said flat portion of said gasket, a neck portion to said gasket integral with said flat portion, surrounding said axle, a holding ring member surrounding said neck portion to force the same toward said axle, said 35 holding ring member comprising a split ring, adjacent ends to said split ring, a clamping bolt with a nut for drawing said ends together, and an extension hinged to said clamping bolt adapted to reach outside said pocket to be turned by a 40 tool. 45

7. An oil sealing device adapted for use between the walls of a narrow pocket around an axle in a journal box, comprising a body plate having a hole therethrough, through which 50 passes said axle, a gasket, a flat portion to said gasket between one of said walls and said body plate and surrounding said axle, wedging means between said body plate and the other of said walls to force said body plate to compress said 55

- flat portion of said gasket against the wall it adjoins, a neck portion to said gasket integral with said flat portion, surrounding said axle, a holding ring member surrounding said neck portion
- 5 to force the same toward said axle, said holding ring member comprising a split ring, adjacent ends to said split ring, a clamping bolt with a nut for drawing said ends together, said holding ring member comprising a split ring, two out-
- 10 turned ends to said split ring, a nut next to one of said ends, a bolt passing through both of said ends, engaging said nut, a sleeve fixed to the other of said ends, surrounding said bolt and positioned to extend away from said ends, a tooth
- 15 on the outer end of said sleeve, a lug on said bolt, adapted to engage said tooth, a compression

spring surrounding said sleeve next to the out-turned ring end having said sleeve, and a shoulder on said bolt engaging said compression spring.

8. In an oil sealing device adapted for use 5 between walls of a pocket around a shaft in a journal box, a compressible sealing ring, surrounding and in contact with said shaft, a split ring enveloping said sealing ring, adjacent ends to said split ring, turnable clamping means for 10 adjustably drawing said ends toward one another, said clamping means including a hinged extension, adapted to be lifted in said pocket, to be connected with a manually turned tool.

ERNEST ARMSTRONG. 15
JOHN EDWARD THEBAUD.
